UNITED STATES PATENT OFFICE.

CHARLES PRENTICE TURNER, OF STEELTON, PENNSYLVANIA.

MECHANISM FOR OPERATING THE REVERSING VALVES OF REGENERATIVE FURNACES.

Application filed November 2, 1921. Serial No. 512,803.

To all whom it may concern:

Be it known that I, CHARLES PRENTICE TURNER, a citizen of the United States, and residing at Steelton, Dauphin County, State of Pennsylvania, have invented certain new and useful Improvements in Mechanism for Operating the Reversing Valves of Regenerative Furnaces, of which the following is a specification.

10 The present invention relates to mechanism for operating the reversing valves of regenerative furnaces.

In operating regenerative furnaces and particularly open hearth furnaces, it is customary to supply producer gas and air through separate conduits to the hearth or combustion chamber where these gases intermingle and burn, the hot products of combustion passing out through two similar passages from the opposite end of the furnace to the stack or first to one or more waste heat boilers to the stack and thence to the atmosphere. Each of the four passages has an enlargement or chamber in which is located checker work, of well known type, and each passage is adapted to serve as either an inlet passage or outlet passage. The hot gases of combustion passing through the two passages serving as outlet passages, heat the checker chambers, and after the chambers are sufficiently heated the direction of flow of gas and air to the furnace is reversed, the producer gas and air then flowing through the checker chambers which have just been heated by the exhaust gases, so that before they reach the combustion chamber their temperatures have been raised to a high degree. The former gas and air inlet passageways have now become outlet conduits for the burned gases, a large proportion of the heat of these gases being absorbed by the checker chambers. Reversal of the furnace takes place usually at regular intervals of time, such reversal being effected by the manipulation of certain valves which control the flow of gas and air to the combustion chamber and the flow of hot products of combustion to the stack.

At the instant of reversal the gas and air inlet passages contain considerable quantities of unburned gas and air which has been heated in the checker chambers to a high temperature, and if precautions are not taken this gas and air will mix in the flues leading to the stack or in the stack itself and cause an explosion. Such explosions

are not serious when the gases have immediate outlet to the atmosphere, as through the stack, but where waste-heat boilers are employed, as is often the case with modern open hearth furnaces, such explosions may result in serious damage to the boiler setting and flues.

It has been found that these explosions may be avoided by preventing the intermingling of the hot unburned gas and heated air at the moment of reversal. By manipulating the valves so that the heated air is prevented from passing to the stack until the hot unburned gases have escaped all possibility of explosion is avoided.

It is the object of the present invention to provide mechanism whereby the valves of a regenerative furnace may be automatically opened and closed upon reversal of the furnace in such sequence that this intermingling of heated gas and air in the waste heat boiler or adjacent flues is prevented. The mechanism is electrically operated and is controlled by a master switch, which is the only member to be manually operated to effect the reversal, the remainder of the operation being entirely automatic. The valves are all mechanically connected to a single motor which is controlled by the master switch. The mechanical connections between the valves and motor are such that the valves are operated in proper sequence as the motor revolves in one direction.

In my copending application, Serial No. 512,804 filed Nov. 2, 1921, is disclosed mechanism of a somewhat similar character but in which the valves are provided with individual motors for operating the same, which motors are controlled by a single master switch and a circuit making and breaking device. In certain instances it is necessary or desirable to employ individual motors while in other instances a single motor and mechanical connections between the motor and valves is preferable.

The invention has many novel features as will be apparent to one skilled in the art as is disclosed in the following descriptions and in the accompanying drawings, in which:

Figure 1 is a top plan view of the gas inlet and outlet valves of a regenerative furnace, portions being broken away to show the checker chambers;

Figures 2, 3 and 4 are sections on the lines 2—2; 3—3; 4—4 respectively of Figure 1;

Figure 5 is a top plan view, partly broken away, of a portion of the valve operating mechanism;

Figure 6 is a front elevation of the same showing diagrammatically certain of the electrical circuits;

Figure 7 is a section on the line 7-7 of Figure 6;

Figure 8 is a section on line 8-8 of Figure 6;

Figures 9 and 10 are sections on lines 9-9 and 10-10 respectively of Figure 6;

Figure 11 is a side view of a portion of a modified form of the valve operating mechanism;

Figure 12 is a similar view of another portion of this modified mechanism;

Figure 13 is a series of diagrams showing the relative positions of the valves and the sequence of movements followed in effecting a reversal; and

Figure 14 is a diagrammatic view of an electromechanical mechanism for retarding the speed of the operating motor temporarily during the reversal.

The hearth or combustion chamber of the furnace is not illustrated in the drawings but it will be understood that the flues 10, 11, 12 and 13 shown in Figure 1 are the gas conducting flues, the enlargements 10', 11', 12' and 13' of these flues constituting the checker chambers, although the actual checker work is not illustrated. The flues 10 and 11 may serve as gas and air inlet flues respectively, in which case both flues 12 and 13 serve as outlet flues for the hot products of combustion. After a reversal of the gas flow flues 12 and 13 serve as air and gas inlet flues respectively and flues 10 and 11 as outlet conduits for the products of combustion.

Each of these flues has, at its forward end, two control valves, one of which controls the flow of fresh gas or air as the case may be to the furnace and the other controls the flow of products of combustion to the stack or waste heat boiler. These valves are illustrated diagrammatically in Figure 1, the valves G^t and G^s controlling the flow of gas into flue 10 and the hot products of combustion out of this flue, and the valves A^t and A^s respectively control the flow of air into the flue 11 and the hot products of combustion out of this flue to the stack. The valves on the opposite side of the furnace are similarly arranged and are indicated at A^{1t}, A^{1s}, G^{1s} and G^{1t}. The main gas supply flue is shown at 14, the gas intake to this flue being illustrated at 15, and the stack is indicated at 16. Dampers 17 and 18 respectively are provided for blocking passages 19 and 20 for conducting the hot products of combustion to the stack so that these products of combustion may be caused to pass through valve controlled

openings 21 and 22 to the waste heat boiler (not shown) from whence they pass to the stack. When the waste-heat boiler is not in use the dampers are open so that the hot gases may flow directly to the stack 70 16. In Figures 2 and 4 respectively, the valves G^t and G^s are illustrated and it will be understood that the remaining valves are similarly constructed, being vertically movable to open and close the various 75 passages which they control.

Referring to Figure 6 it will be seen that each of the valves on the right hand side of the furnace is provided with a vertically disposed stem, the upper end of which is 80 pivotally hung from a valve operating lever. These valve operating levers are indicated at L^t, L^s, M^t and M^s respectively. The valve operating mechanism on the left hand side of the stack is not illustrated, but 85 it will be understood that such mechanism is an exact duplicate of the mechanism illustrated. Each of levers L^t, L^s, M^t and M^s has one end rotatably mounted upon a long shaft 24 which is in turn rotatably supported in the framework.

Upward and downward movement of the levers just mentioned results in the opening and closing of the valves and this movement is brought about by the operation of a 95 large motor R mounted on the framework and which is mechanically connected to each of the valve levers. This motor is connected by means of a chain and gear to the shaft 26, which is in turn geared to the 100 shaft 24. The shaft 24 is geared to two countershafts 27 and 28 so that rotation of the motor R results in rotation of these countershafts, though at greatly reduced speed.

The countershaft 27 has a crank arm fixed to each end, these crank arms extending in diametrically opposite directions. The right hand crank arm 29 has a connecting rod 30 pivotally secured thereto, this connecting rod having a spindle-like end portion 30' which passes through an opening in a short cross piece 31 rotatably secured to lever L^t. The reduced extension 30' of the connecting rod is adapted to slide 115 through the opening in this cross piece, the limits of this sliding motion being determined by the relative positions of the shoulder 30² and nut 30³ at the outer end of the connecting rod. It will be seen that rotation of countershaft 27 through a complete circle will effect the raising and lowering of lever L^t but that, due to the lost motion of the connecting rod, the valve G^t will be in its lowest position, or seated, during the 120 time that the crank arm 29 is in the lower part of its swing and will only be raised when the crank arm is in the upper part of its swing.

In Figure 8 the crank arm 32 is illustrated 130

in dotted lines and is illustrated near the top of its swing, the lever L^s being raised and the valve G^s unseated, as shown in Figure 6. Countershaft 28 is provided with similar crank arms 33 and 34 respectively which are connected by connecting rods 35 and 36 to levers M^s and M^t respectively. In this instance however the crank arms 33 and 34 are not diametrically opposite but are arranged at an angle to each other. The position of the crank arm 34 corresponds substantially to that of the crank arm 29 while the crank arm 33 is about 60° behind the crank arm 32, the direction of rotation being indicated by the arrows in Figures 7 and 8. While countershafts 27 and 28 are not connected to each other, yet they are driven at the same angular velocity by shaft 24, and the various crank arms occupy, at all times, the same angular relationship to each other. The interval of time during which each of the valves remain in closed position depends upon the design of the connecting rod, that is upon the amount of lost motion between the crank arm and the operating levers and the motor speed, while the sequence of operation of the valves depends upon the direction of rotation of countershafts 27 and 28 and upon the angular relationship which the several crank arms bear to each other. As the countershafts are driven in the direction of the arrows it will be seen that the valves G^t and A^t will be opened and closed simultaneously while the valve A^s will be opened considerably later than gas valve G^s , thus permitting the hot gas to escape through the boiler to the stack before the hot air is liberated. Crank 32 passes its dead center in advance of the crank 33 and the lost motion connection between the connecting rod 35 and the lever M^s is so designed that the period during which valve G^s is open and valve A^s closed, is of considerable duration.

The electric circuits for controlling the operation of the motor R are illustrated in Figure 6. The motor armature is indicated at 40 and its field at 41. Lead wires to a suitable generator are indicated at 42 and it will be seen that the circuit through the armature is controlled by a switch. This switch comprises a stationary contact 43 and a moving contact 44 which also constitutes the armature of an electro-magnet 45. When this electro-magnet 45 is energized it attracts the armature 44 and closes the circuit through the motor armature 40. As soon as the magnet 45 is deenergized, however, the circuit through the armature 40 is broken and at the same time a resistance 46 thrown into action, the switch member 44 being moved by a spring 47 so that its opposite end is thrown into contact with a stationary contact 48. The resistance 46 brings about a braking influence tending to immediately stop the motor armature from rotating.

A main or master switch is indicated at S and two stationary contacts at 49 and 50. The switch plate S may be brought into contact with either of the stationary contacts. Mounted upon shaft 27 is a cylindrical drum 51 of insulating material having mounted upon its outer surface two semicylindrical contact plates 52 and 53. Spring contacts 54, 55, 56 and 57 have their ends resting against this cylinder, contacts 54 and 55 being adapted to brush against moving contact 53 as the cylinder is revolved and contacts 56 and 57 being adapted to engage moving contact 52. Contacts 52 and 53 are on diametrically opposite sides of the drum 51 but each extends slightly more than one-half of the distance around it. Spring contacts 55 and 57 are electrically connected to the negative terminal of the generator (not illustrated) and spring contacts 54 and 56 are connected to contacts 49 and 50 respectively.

Assuming the switch S to be in its full line position it will be seen that a circuit will be completed through electro-magnet 45 provided that spring contacts 56 and 57 are electrically connected by contact 52. The switch blade 44 will then be operated and the circuit closed through motor R . Rotation of countershaft 27 then commences and this rotation will continue until this shaft has turned through 180° , when contact 52 will move from under contacts 56 and 57 thus breaking the circuit and stopping the motor. Rotation of the countershaft 27, and the other countershafts, through 180° effects a reversal of the valves. Contact 53 is then engaged by spring contacts 54 and 55 and it only remains for the operator to shift the switch S to its dotted line position to again energize magnet 45 and effect a second reversal of the valves. The drum 51 therefore constitutes an automatic circuit breaking device which breaks the circuit when the valve reversal is completed. Except for the operation of the switch S the operation of the mechanism is entirely automatic and requires no expert knowledge or manual assistance on the part of the furnace operator, who simply effects the reversal at certain predetermined times.

In Figure 13 the diagrams a , b , c , d , e , f and g illustrate the relative positions of the valves in two complete reversals. In the diagram a , the valves A^t and G^t are shown to be open and valves A^s and G^s closed. On the opposite side of the furnace the valves A^u and G^u are closed while valves G^{1s} and A^{1s} are open. When the switch S is operated the first result of the movement of motor R is to lower the valves G^t , A^t , A^{1s} , G^{1s} , so that all of the valves are closed, as indicated in diagram b . The closure of the gas valves on both sides prevents wastage of gas to the stack during reversal, that is,

a flow of gas for instance from the flue 14 through the valves G' and G^s and the flue 19 directly to the stack. Further operation of the mechanism results in the raising of valves G^s, A^u and G^u, the valve A^s remaining closed. The return flow of the gas to the furnace has then started but it will be seen that while the gas valve to the stack is open so that the hot unburned gas in the checker chamber 10' can pass to the stack, the heated air in the checker chamber 11' cannot pass to the stack, so that there is no explosive mixture formed in the waste heat boiler. Continued operation of the mechanism finally results in the raising of valve A^s as shown in diagram *d* after which the mechanism comes to rest, having effected a complete reversal. The interval of time between the raising of the valve G^s and valve 20 A^s depends, as before explained, upon the angular relationship of the cranks 32 and 33, the design of the connecting rods, and the speed of motor R.

Movement of the switch S will again effect 25 a reversal to original position, the valves passing through the positions illustrated in diagrams *e*, *f* and *g*, the diagram *g* being similar to diagram *a*.

Instead of utilizing the cranks and connecting rods illustrated in Figures 5, 6, 7 and 8 the valve operating levers may be operated by cams mounted upon the counter-shafts as shown in Figures 11 and 12. Figure 11 corresponds to Figure 8 and Figure 35 12 corresponds to Figure 7. The movements 40 of the valves effected by the cams illustrated is exactly the same as in the first instance, the cams being so shaped that the valves are operated in the proper sequence. Cams 60 60 and 61 correspond to cranks 29 and 32 respectively and cams 62 and 63 correspond to cranks 33 and 34 respectively, each of these cams having a cam surface against which a roller mounted on the corresponding valve 45 operating lever is adapted to bear, and to be held thereagainst by the weight of the valve suspended from the outer end of the lever. The cams are rotated in the direction indicated by the arrows and it will be seen that 50 cam 62 is just beginning to open valve A^s. Valve A^s is fully open when the roller of the valve operating lever is resting on the peak of this cam and the shafts stop rotating with the cam in this position. The gas valve 55 to the stack is opened by cam 61 considerably in advance of the opening of valve A^s and is held open, the corresponding roller passing over its circular peak portion while valve A^s is opening. During this movement valves 60 A' and G' are not operated, but upon movement of cam 62 through a further angle valves A^s and G^s will be closed, and soon after, valves A' and G' opened.

While the arrangement of the cranks or 65 cams in angular relationship to each other,

as explained, is generally sufficient to effect the movement of the valves at the desired times, additional means may be provided to increase the length of the pause between the opening of valve G^s and the opening of valve A^s. This may be brought about, for instance, by the utilization of means for slowing down the motor temporarily. For instance, in Figure 14 is illustrated diagrammatically means whereby the resistance of the motor may be materially decreased when the countershaft has reached a predetermined angular position. The motor field 41 has connected in series therewith a resistance 70 controlled by rheostat arm 71 which in turn is operated by a cam 72 fixed on the countershaft 27. After the valve G^s has been opened the cam 72 becomes operative to move the rheostat arm 71 to the right against the action of the spring 73, and to thereby cut out the resistance 70, and cutting down the speed of the motor until the cam has allowed spring 73 to return arm 71 to original position, at which time the motor resumes its original speed.

Other devices of this character might be employed if desired and in general, the design and arrangement of the component parts of the invention may be greatly modified, the invention not being limited to the mechanism described herein and illustrated by way of example.

Having thus described the invention what I claim as new and desire to secure by Letters Patent is:

1. In apparatus of the class described, the combination of a plurality of valves to be opened in sequence, a motor, mechanism driven by the motor for opening the valves sequentially, and means for retarding the speed of the motor during a predetermined period of the operation of said mechanism, whereby the lag between times of opening the valves may be increased.

2. A valve operating mechanism for regenerative furnaces including in combination, an electric motor operatively connected to the valve, a rotatable member driven by the motor and having actuating means thereon, and means adapted to be operated by said actuating means for temporarily reducing the motor speed.

3. A valve operating mechanism for regenerative furnaces including in combination, an electric motor operatively connected to the valve, a rotatable member driven by the motor and having actuating means thereon, and means for cutting out the resistance of the motor field operated by said actuating means for temporarily reducing the motor speed.

4. A valve operating mechanism for regenerative furnaces including in combination, an electric motor operatively connected to the valve, a rotatable member driven

by the motor and having actuating means thereon, and means adapted to be operated by said actuating means for temporarily reducing the motor speed, said means including a resistance element connected with the motor field circuit and a rheostat arm for varying said resistance.

5. A valve operating mechanism for regenerative furnaces including in combination, an electric motor operatively connected to the valve, a rotatable member driven by the motor and having actuating means thereon, and means adapted to be operated by said actuating means for temporarily reducing the motor speed, said means including a resistance connected in the motor field, and a pivoted switch arm controlling the amount of such resistance in the motor field circuit, said pivoted arm operatively engaging and being actuated by said cam.

10. A valve operating mechanism for regenerative furnaces including, in combination, four valves, a crank arm corresponding to each valve, each crank arm being mounted 15 on a rotatable member operatively connected to the motor, and means connecting each crank arm with the corresponding valve.

15. A valve operating mechanism for regenerative furnaces including in combination, four valves, a crank arm for each valve, and connected thereto, two countershafts each countershaft supporting two crank arms, a motor, and means operatively connecting the motor and countershafts.

20. A valve operating mechanism for regenerative furnaces including, in combination, an electric motor, four valves, and means operatively connecting said motor and valves including four crank arms each 25 rotatable about an axis, the angular relationship of the crank arms determining the order of movement of the valves.

25. In a regenerative furnace, the combination of air and gas regenerators for each end of the furnace, inlet and outlet valves for the regenerators, a drive shaft for operating the valves for each pair of associated regenerators, means for driving the drive shaft, and motion converting means between 30 the drive shafts and the valves and arranged to produce cyclic operation of the latter wherein an air regenerator outlet valve is opened after its associated gas regenerator valve is opened.

35. 10. In a regenerative furnace, the combination of air and gas regenerators for each end of the furnace, inlet and outlet valves for the regenerators, a rotary shaft for each pair of associated regenerators, means to secure synchronous rotation of the shafts, motion-transmitting means between the shafts and the valves for converting rotary motion of the shafts into rectilinear motion of the valves, said means being arranged for reversible cyclic operation of the valves of the

regenerators and the air regenerator outlet valve being opened after the gas regenerator outlet valve in each cycle.

40. 11. In a regenerative furnace, the combination of air and gas regenerators for each end of the furnace, inlet and outlet valves for the regenerators, means for producing reversible cyclic operation of the valves wherein an air regenerator outlet valve is opened after a gas regenerator outlet valve, said means including a rotary shaft for each pair of associated regenerators, means for driving the shafts synchronously, and means for converting rotary motion of the shafts into rectilinear motion of the valves, said 45 motion-converting means for the air regenerator valves lagging in opening the latter with respect to the motion-converting means for opening the associated regenerator outlet valves, and means for stopping the driving means upon a completion of a cycle of operation of said valves.

45. 12. In a regenerative furnace, the combination of air and gas regenerators for each end of the furnace, inlet and outlet valves for the regenerators, and means for producing reversible cyclic operation of said valves wherein an air regenerator valve is opened after a gas regenerator valve is opened including shafts for each pair of associated regenerators, a motor for driving the shafts, motion translating means between the shafts and the valves, the motion translating means of the air regenerator valves lagging with respect to the motion translating means for the associated gas regenerator outlet valves, and means for rendering the motor ineffective upon a predetermined angular movement of one of the shafts wherein a cycle of operation of said valves is completed.

50. 13. In a regenerative furnace, the combination of air and gas regenerators for each end of the furnace, inlet and outlet valves for the regenerators, and means for producing reversible cyclic operation of said valves wherein an air regenerator outlet valve is opened after a gas regenerator outlet valve, said means including a shaft for each pair of associated regenerators, an electric motor for driving the shafts, motion translating means between the shafts and the valves for opening and closing the latter by rotary motion of said shafts, said motion translating means between the shafts and the air regenerator outlet valves lagging in effecting opening movement of the latter with respect to the motion translating means for opening the outlet valves of the associated gas regenerators, a movable contact member operated by one of the shafts and carrying a pair of overlapping contacts, a pair of contacts adapted to engage with each of said overlapping contacts, and a switch for completing a circuit to said motor and a pair of

contacts in engagement with one of the overlapping contacts.

14. In a regenerative furnace, the combination of air and gas regenerators for each 5 end of the furnace, inlet and outlet valves for the regenerators, and means for producing cyclic operation of said valves wherein an air regenerator outlet valve is opened after its associated gas regenerator outlet 10 valve is opened, said means including a shaft for each pair of associated regenerators, an electric motor for driving the shafts, motion translating means between the shafts and the valves for converting rotary motion of the shafts into rectilinear motion of the valves, said motion translating means for the air regenerator outlet valves lagging in operation with respect to the motion translating means for the associated gas regenerator outlet valves, a drum operated by one of the shafts, overlapping segmental contacts on the drum, a pair of contacts for engagement with each of the segmental overlapping contacts, a switch for 20 completing a circuit to said motor and a pair of contacts in engagement with one of said overlapping segmental contacts, and means for applying a braking effect to said motor when a segmental contact passes out 25 of engagement with a pair of contacts upon the completion of a cycle of valve operation to stop the motor to stop the shafts and motion translating means with the other segmental contact in engagement with the 30 other pair of contacts.

15. In a regenerative furnace, the combination of air and gas regenerators for each

end of the furnace, inlet and outlet valves for the regenerators, and means for producing cyclic operation of said valves wherein an air regenerator outlet valve is opened after its associated gas regenerator outlet valve is opened, said means including a shaft for each pair of associated regenerators, an electric motor for driving the shafts, motion translating means between the shafts and the valves for converting rotary motion of the shafts into rectilinear motion of the valves, said motion translating means for the air regenerator outlet valves lagging in operation with respect to the motion translating means for the associated gas regenerator outlet valves, a drum operated by one of the shafts, overlapping segmental contacts on the drum, a pair of contacts for engagement with each of the segmental overlapping contacts, a master switch for completing a circuit to said motor and a pair of contacts in engagement with one of said overlapping segmental contacts, a load for said motor, a circuit for the motor and the load, a switch for opening and closing said circuit, means for closing said switch upon a segmental contact passing out of engagement with a pair of contacts, and means for opening said switch when said master switch is shifted to complete the motor circuit through the other overlapping segmental contact and its pair of associated contacts.

In testimony whereof I hereunto affix my signature.

CHARLES PRENTICE TURNER.
